WELT SUPPORT

John F. Smith, Quincy, and William C. Card, Jr., Winthrop, Mass., assignors to Campi Shoe Machinery Corporation, Boston, Mass., a corporation of Delaware

Application June 24, 1937, Serial No. 150,050

26 Claims. (Cl. 12—33)

This invention relates to the manufacture of footwear, and more particularly to an apparatus for engaging in the welt crease of a shoe to support the welt against pressure from beneath, as 5 in sole-affixing, sole-laying or channel-laying operations.

A general object of the invention is to provide a welt hold-down having improved features of construction.

10 More particularly, objects of the invention are to provide a welt hold-down having a wide range of adjustment so that it can handle shoes of widely varied sizes and shapes, which is rugged in construction, easy to manipulate, and well suited for attachment to and cooperation with 15 existing or other suitable types of presses.

Other objects of the invention will in part be obvious and will in part appear hereinafter.

The invention accordingly comprises the features of construction, combination of elements and arrangement of parts, which will be exemplified in the construction hereinafter set forth and the scope of the invention will be indicated in the claims.

25 For a fuller understanding of the nature and objects of the invention, reference should be had to the following detailed description taken in connection with the accompanying drawings, in which:

30 Fig. 1 is a plan view of a press equipped with a welt hold-down embodying features of this invention, part of the bow member being broken away better to show the top of the welt hold-down construction;

35 Fig. 2 is a side elevation of the press shown in Fig. 1, parts thereof being broken away and shown in section better to illustrate the construction;

Fig. 3 is a horizontal, sectional view on an enlarged scale taken substantially along line 3—3 of Fig. 2;

Fig. 4 is a transverse, vertical sectional view taken substantially along line 4—4 of Fig. 2;

Fig. 5 is a fragmentary perspective view showing a detail of a connection between adjoining platen elements;

Fig. 6 is a horizontal sectional view similar to Fig. 3 but showing another embodiment of the invention;

50 Fig. 7 is a side elevation of the structure shown in Fig. 6 taken substantially along line 7—7 of that figure;

Fig. 8 is a fragmentary, horizontal sectional view showing the end portion of platens embodying another form of the invention;

Fig. 9 is a horizontal sectional view similar to Fig. 3 but showing a further embodiment of the invention; and

Fig. 10 is a longitudinal vertical sectional view taken along line 10—10 of Fig. 9.

At the present time, many welt shoes are made with a cement bond between the outsole and the welt. The cement affixation of the outsole is usually effected in a press which urges the sole up against the shoe which is held against upward displacement. This pressure from below tends to roll or curve the welt extension unless the latter is adequately supported. The device of the present invention affords such support for the welt and is generally useful in cement sole 15 affixing operations and other operations in which pressure is applied to the welt extension from below, such as sole-leveling and channel-laying. The device of the present invention is adapted to be mounted on or to be used in conjunction 20 with a press capable of carrying out any of these operations.

Referring more particularly to the drawings and first to Figs. 1 and 2, there is shown a press comprising a pocketed base member 10 having 25 fixedly attached thereto a longitudinal bow member 11 carrying a heel post 12 and a threaded toe post 13 which is adapted to be locked at any desired height with respect to the bow member by means of the lock nut 14. The lower end of the 20 toe post carries a shoe engaging cushion 15. The pocketed portion of the base 10 carries a pressure pad 16 having an upper diaphragm which is adapted to be urged by means of fluid pressure against the bottom of a shoe held in the press. 35 This pressure may be increased in any desired manner, as, for example, by means of a fluid inlet and outlet conduit 17 which is adapted to be operated in a manner well known to the art. The entire press may conveniently be mounted 40 on a belt or other conveyor, and as thus far described is of more or less conventional construction forming no part of the present invention except insofar as it is utilized in combination with the features about to be described.

45 The device for supporting the welt may conveniently be mounted on the toe post 13, although this is not essential since it may be otherwise mounted on or with respect to the press. When it is to be mounted on the toe post, the latter is 50 provided with a sleeve or collar 18 which is threaded over the toe post and held at a desired vertical height by means of a lock nut 19. A support 20 is swingably mounted on the sleeve 18 by means of inwardly extending trunnions 21 55

and 22 which are arranged along a common axis extending transversely of the press so that the support 20 may tilt longitudinally. The support has a forwardly projecting tongue 23 provided with an elongate longitudinal slot or opening 24 and also has laterally extending wings 25 and 26 respectively provided with openings 27 and 28. Adjacent the rear of opening 27, a pivot 29 swingably carries upper and lower plates 30 each provided with an elongate slot 31. A similar pivot 32 is positioned at the rear end of the opening 28 and pivotally carries upper and lower plates 33 provided with elongate slots 34. The plates 30 and 33 are adapted to swing across their respective wings 25 and 26 with their slots in registry with the openings in such wings.

The slot 24 in the forwardly projecting tongue 23 has a headed post 35 extending downwardly therethrough. The lower end of post 35 is fixedly mounted in a transverse bar comprising a toe platen casting 36, and a compression spring 37 surrounds the post 35 and seats between a collar 38 adjacent the toe platen bar and a spring seat or washer 39 adjacent the tongue 23, so as normally to urge the platen bar downwardly toward the pad diaphragm. The central portion of the toe platen casting at its lower rearwardly facing edge is tapered into a platen portion 40 which is adapted to seat over the welt extension at the toe or tip of the shoe as indicated in Fig. 2 where the shoe is shown in dotted outline. Extending laterally from the central portion of the toe platen casting are end portions 41 and 42 respectively, provided with elongate transversely extending slots 43 and 44.

A pair of side platens 45 and 46 are provided, each having downwardly extending attenuated inner edge portions 47 and 48 adapted to enter in the welt crease at the opposite sides of the forepart of the shoe so as to hold down the welt. The forward ends of platens 45 and 46 are respectively bifurcated at 49 and 50, the upper fork being shown best in Fig. 3. The lower fork extends beneath the adjacent end portions 41 or 42 of the toe platen casting. A threaded pin 51 (Fig. 3) is screwed through the upper and lower forks 49 and passes through the slot 43 along which it is adapted to slide. This pin has an enlarged head 52 facilitating assembly and disassembly of the platen 45 with the end portion 41. The forks 50 on the platen 46 have a similar pin 53 screwed therein and passing through the slot 44. The slots 43 and 44 may be of different extents, if desired, as shown in the drawings, or only one elongate slot need be used so long as the required relative bodily movement of the platens toward and from each other is provided. The pin 53 has an enlarged head 54, and the latter is connected to the head 52 by means of a tension spring 55 which serves normally to urge the platens 45 and 46 toward each other to the extent permitted by the slots 43 and 44 in the toe platen casting.

Toward its rear end the side platen 45 has fixedly attached to it an upwardly extending post 56, the upper end of which passes through the registered slots 31 in plates 30 as well as the opening 27 in the wing 25. This post carries a collar 57 limiting its downward movement through the slots 31 and has a spring 58 surrounding it and bearing between a lock nut 59 adjacent the platen and a spring seat 60 adjacent the under-side of the lowermost plate 30.

The side platen 46 also has near its rear end a post 61 the upper end of which projects through

and above the registered slots 34 in plates 33 and through the opening 28 in wing 26. A collar 62 prevents undue downward movement of post 61 and a compression spring 63 surrounds such post and is seated between a lock nut 64 and a spring seat or washer 65.

Preferably, each side platen is provided with a rearwardly extending tail piece which is flexibly articulated thereto. In the illustrated construction, the welt holdown is designed for a left shoe and the side platen 45 is adapted to engage around the outer side of such shoe and is somewhat longer than the opposite platen 46. A tail piece 66 abuts the rear end of platen 45 and has a platen portion 67 forming a continuation of the welt crease engaging portion 47. The tail piece is connected to the platen for relative horizontal and vertical swinging movement with respect thereto. To effect this, the hinge connecting element illustrated in Fig. 5 is employed. The upper edges of the platen and tail piece are mutually coped near their abutting ends to accommodate the connector 68 which has a forwardly extending vertical flange 69 connected by means of a horizontal pivot pin 70 with the rear of the side platen. The connector 68 also has a rearwardly extending horizontal flange 71 connected to the tail piece by means of a vertical pivot pin 72. A leaf spring 73 is confined between the nut 59 and the platen 45 and bears against the upper surface of the tail piece to restrain the upward tilting of the latter under pressure exerted by the pad diaphragm.

The side platen 46 has a similar but preferably somewhat shorter tail piece 74 pivoted thereto in the same manner and similarly restrained against undue upward movement by means of a leaf spring 75. Both tail pieces are limited against undue inward or downward swinging movement by abutment against the adjoining side platen, as illustrated.

In operation, a widely varied assortment of shoes can be accommodated inasmuch as the side platens may be moved bodily toward and from each other by virtue of the sliding joint at 43 or 44 and may also be swung pivotally with respect to the toe platen casting. The under surfaces of the side and toe platens are shaped to be always sufficiently contiguous to give a satisfactory support to the welt at the tip of the shoe. The welt hold-down also is effective for a considerable distance rearwardly into the shank portion of the shoe by virtue of the tail pieces 66 and 74 which are adapted to be accommodated both to the lateral and vertical contours of the shoe bottom. The entire unit is movable longitudinally with respect to the toe post when desired by virtue of the elongate slot 24 and openings 27 and 28. However, this adjustment is not often needed since the shoe is generally fitted into the welt hold-down and has its longitudinal position on the pad more or less controlled thereby.

When pressure is applied beneath the welt, as in cement-affixing a sole thereto, the various welt supporting elements which are entered in the welt crease bear down against the upper surface of the welt and are held thereagainst under pressure of the several springs 37, 58 and 63, which are made strong enough to afford requisite cementing pressure.

The side platens are normally urged toward each other by means of tension springs 76 and 77, respectively extending between posts 56 and 61

and a rearwardly extending finger 78 cast integrally with the support 20.

In Figs. 6 and 7 another arrangement of the platens is shown. These platens are adapted to be suspended on posts 35, 56 and 61 as in the first described form, these posts in turn being suspended from a support 20 (Fig. 1) suitably mounted on the shoe press. The platens comprise a side platen 146 having a tail 174 connected to its free end for vertical swinging movement about a hinge 168. This hinge does not permit horizontal swinging movement, but it will be obvious that if this is desired, it can be provided by means of the arrangement shown in Fig. 5. This platen 15 carries a downward extension 148 shaped to enter the welt crease of a shoe. The unit includes another platen 145 having a tail piece 166 hinge to its free end for vertical swinging movement. Platen 145 has a downward extension 147 adapted to enter the welt crease on the left side of the shoe. A front platen 140 is provided which depends from a transversely extending bar portion 136 of the platen 146, these parts all being integral as illustrated. The post 35 passes through this bar portion 136, the latter having a transverse elongate slot 83 for this purpose. The platen 145 has a forward end portion 149 which is extended transversely so as to overlap the bar portion 136 and this end portion is provided with a transversely elongate slot 79 which accommodates the post 35 while permitting lateral bodily sliding movement between the platen 145 and the remaining platens. The bar portion 136 has a forwardly projecting lug 80 formed thereon and the end portion 149 has a similar lug 81. The forwardly projecting lugs 80 and 81 respectively carry upstanding ears 80' and 81' which are pivotally pinned through the lugs. These ears have aligned bores threaded in opposite directions 40 through which passes a right and left threaded adjusting screw 82 which may be rotated to effect separation or approach of the platens. The platens 145 and 146 may be pivotally swung open and closed about the axes of the pins of ears 80' and 81', the slots 79 and 83 affording suitable accommodation for post 35 when this is done.

Leaf springs such as 173 are provided at the rear of each side platen to urge the respective tail pieces downwardly.

In Fig. 8 an arrangement is shown which is generally similar to that in Figs. 6 and 7 except that it has a spring bias at the toe end of the platens. Here a side platen 246 is formed integrally with a bar portion 236 and a front platen portion 240, the bar 236 being provided with a transverse elongate slot 283. A side platen 245 is also provided and has a transversely extending front end portion 249 provided with a transverse elongate slot 279. These slots are adapted to be registered and to have a front post 35 passed therethrough to form a pivot about which the platens may both swing and slide. Lugs 280 and 281 respectively project forwardly from the opposed platen structures and are connected by a tension spring 255 which normally urges the platens into their closest lateral relation. The platens may otherwise be constructed as in Figs. 1 or 6, and are adapted to be suspended from a press by any suitable means, such as that shown in Fig. 1.

A further embodiment of the invention is shown in Figs. 9 and 10 where rigid metallic side platens 345 and 346 are provided and respectively have overlapped front end portions 336 and 349, the latter being provided with a transverse elongate

slot 379. A post 35 extends through this slot and is fixed in the end portion 336 of platen 346. Toward their rear or free ends these side platens are provided with enlargements for accommodating supporting posts 56 and 61.

Extending from the underside of the platens is a continuous heavy elastic rubber strip 84, the inner edge of which is somewhat beveled as at 85 to facilitate its entry in the welt crease around the end of a shoe, the continuous rubber strip in this respect performing the function of platen portions 40, 47 and 48 in the first described form. At its forward end the rubber strip 84 is fixedly attached by means of a screw 85' to the adjacent toe portion of the platen end 336. At its free rear ends the rubber strip 84 is screwed to platen 86 each of which has an upstanding spring seat 87 attached thereto by means of a screw 88 which passes through a longitudinal slot 89 provided in the rear end of each of platens 345 and 346. Compression springs 90 bear between the spring seats 87 and the respective post-accommodating enlargements on the side platens, being guided on pins 91 which are slidable through such enlargements. The rubber strip 84 is otherwise free from attachment to the metal platens. By virtue of this arrangement, when the structure is pivoted or laterally widened the ends of the rubber welt hold down strips are free to move with respect to the metal platens so that the strip may readily accommodate itself to the shoe.

The entire arrangement shown in Figs. 9 and 10 is adapted to be supported on a press in the same manner as in the preceding forms, or in any other suitable manner.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described our invention, what we claim as new and desire to secure by Letters Patent is:

1. A welt support unit, comprising a pair of relatively movable platens shaped to fit in the welt crease on opposite sides of a shoe, a bar spanning the ends of said platens, at least one of said platens having a laterally extending free sliding connection with said bar whereby it may move bodily toward and from the other platen, and at least one of said platens being swingably connected with said bar about only a single pivot whereby it may freely swing with respect to the remaining platen, and means normally urging said platens toward each other along said sliding connection.

2. A welt support unit, comprising a pair of relatively movable platens shaped to fit in the welt crease on opposite sides of a shoe, a bar spanning the ends of said platens, pivotal connections between the ends of said platens and said bar, at least one of said connections being arranged to provide lateral sliding movement between its platen and said bar, spring means urging the pivoted ends of said platens together, and added spring means urging the free ends of said platens together.

3. A welt support unit, comprising a transverse

bar, platens fitted to enter the welt crease on opposite sides of a shoe each having an end pivotally and slidably mounted on said bar, and spring means urging the pivoted ends and the free ends of said platens together.

4. A welt support unit, comprising a transverse bar, side platens fitted to enter the welt crease on opposite sides of a shoe each having an end pivotally mounted on said bar, at least one of said platens being also freely slidable along said bar for bodily movement toward and from the remaining side platen, an end platen carried by said bar between said side platens in position to enter the welt crease at the end of said shoe, and spring means normally urging the pivoted ends of said side platens toward each other.

5. A welt support unit, comprising a transverse bar, side platens fitted to enter the welt crease on opposite sides of a shoe each having an end pivotally mounted on said bar, at least one of said platens being also slidably along said bar for bodily movement toward and from the remaining side platen, an end platen carried by said bar between said side platens in position to enter the welt crease at the end of a shoe, spring means urging the pivoted ends of said side platens together, and added spring means urging the free ends of said platens together.

6. A welt support unit, comprising a transverse bar having elongate slots at its opposite ends and having a downwardly extending central platen adapted to fit over the welt at the toe end of a shoe, a pair of side platens fitted to enter the welt crease on opposite sides of a shoe and each having a pivot pin pivotally and slidably accommodated in said bar slots, a tension spring connecting said pins, means extending upwardly from the free ends of said side platens above the top of such shoe, and spring means urging said upwardly extending means together.

7. In a shoe press, a weld hold-down unit comprising a support mounted on the press and having laterally spaced openings, a post extending downwardly from said support and having a transverse bar at its lower end, a platen on the central portion of said bar shaped to fit over the welt at the toe of a shoe in said press, side platens pivotally mounted on said bar at each side of said central platen and shaped to enter the welt crease on opposite sides of said shoe, side posts extending upwardly from the free ends of each of said side platens and respectively passing through said support openings, and means retaining said side posts for loose motion in said openings to provide for opening and closing movement of said side platens.

8. In a shoe press, a welt hold-down unit comprising a support mounted on the press and having a forward opening and rearward laterally spaced openings, a post extending through said forward opening and having a transverse bar at its lower end, a platen on the central portion of said bar shaped to fit over the welt at the toe of a shoe in said press, side platens pivotally mounted on said bar at each side of said central platen and shaped to enter the welt crease on opposite sides of said shoe, side posts respectively passing through said laterally spaced openings in loose motion relation therewith and having their lower ends attached to the free ends of said side platens, and spring means urging said posts and platens downwardly with respect to said support.

9. In a shoe press, a welt hold-down unit comprising a support mounted on the press and hav-

ing a forward opening and rearward laterally spaced openings, a post extending through said forward opening and having a transverse bar at its lower end, a platen on the central portion of said bar shaped to fit over the welt at the toe of a shoe in said press, side platens pivotally and laterally slidably mounted on said bar at each side of said central platen and shaped to enter the welt crease on opposite sides of said shoe, side posts respectively passing through said laterally spaced openings and having their lower ends attached to the free ends of said platens, said side posts having a loose motion relation with their respective support openings permitting their relative approach, spring means urging the pivoted ends of said side platens together, and spring means urging said side posts together.

10. In a shoe press, a welt hold-down unit comprising a support mounted on the press and having a forward opening and rearward laterally spaced openings, a post extending through said forward opening and having a transverse bar at its lower end, a platen on the central portion of said bar shaped to fit over the welt at the toe of a shoe in said press, side platens pivotally and laterally slidably mounted on said bar at each side of said central platen and shaped to enter the welt crease on opposite sides of said shoe, side posts respectively passing through said laterally spaced openings and having their lower ends attached to the free ends of said platens, said side posts having a loose motion relation with their respective support openings permitting their relative approach, spring means urging the pivoted ends of said side platens together, spring means urging said side posts together and spring means urging said posts and platens downwardly with respect to said support.

11. In a shoe press, a welt hold-down unit comprising a support mounted on the press and having a forward opening and rearward laterally spaced openings, a post extending through said forward opening and having a transverse bar at its lower end, a platen on the central portion of said bar shaped to fit over the welt at the toe of a shoe in said press, side platens pivotally and laterally slidably mounted on said bar at each side of said central platen and shaped to enter the welt crease on opposite sides of said shoe, side posts respectively passing through said laterally spaced openings and having their lower ends attached to the free ends of said platens, said side posts having a loose motion relation with their respective support openings permitting their relative approach, spring means urging the pivoted ends of said side platens together and spring means urging said side posts together, said support openings all having longitudinal extent whereby said posts and platens may be shifted as a unit longitudinally of said press.

12. A welt support unit comprising a pair of side platens mounted for opening and closing movement with respect to each other and shaped to enter the welt crease on opposite sides of a shoe, and a tail or extension on at least one of said platens extending rearwardly therefrom and shaped to enter the welt crease of said shoe, said platen and tail having a flexible joint therebetween providing for vertical swinging movement of the tail with respect to the platen.

13. A welt support unit comprising a pair of side platens mounted for opening and closing movement with respect to each other and shaped to enter the welt crease on opposite sides of a shoe, and a tail or extension on at least one of

5 said platens extending rearwardly therefrom and shaped to enter the welt crease of said shoe, said platen and tail having a flexible joint therebetween providing for horizontal and vertical swinging movement of the tail with respect to the platen.

10 14. A welt support unit comprising a pair of side platens mounted for opening and closing movement with respect to each other and shaped to enter the welt crease on opposite sides of a shoe, and a tail or extension on at least one of said platens extending rearwardly therefrom and shaped to enter the welt crease of said shoe, said platen and tail having a flexible joint therebetween providing for horizontal and vertical swinging movement of the tail with respect to the platen, and spring means extending from said platen over said tail yieldingly to hold the latter against upward vertical swinging movement.

20 15. In a shoe press, a welt hold-down unit comprising a support mounted on said press for tilting movement about a transverse axis, a pair of side platens suspended from said support, a tail or extension mounted for horizontal and vertical swinging movement on the rear end of at least one of said side platens, said platens and tail being shaped to enter the welt crease of a shoe, and spring means yieldably holding said tail against upward swinging movement with respect to its platen.

25 16. A welt support unit comprising, a support adapted to be mounted in association with a shoe press, side platens mounted on said support and adapted to enter the welt crease on opposite sides of a shoe, the forward ends of said platens being overlapped, a post connecting said overlapped ends, at least one of said ends having a transverse slot accommodating said post to permit lateral bodily movement of said platens toward and from each other.

30 17. A welt support unit comprising, a support adapted to be mounted in association with a shoe press, said platens mounted on said support and adapted to enter the welt crease on opposite sides of a shoe, the forward ends of said platens being overlapped, a post connecting said overlapped ends, at least one of said ends having a transverse slot accommodating said post to permit lateral bodily movement of said platens toward and from each other and means connecting the forward ends of said platens for moving them together at the forward end of a shoe.

35 18. A welt support unit comprising, a support adapted to be mounted in association with a shoe press, welt holding means on said support including a transverse bar, side platens fitted to enter the welt crease on opposite sides of a shoe, one of said platens being integral with said bar and the other being pivotally and laterally slidably mounted on said bar, and an end platen carried by said bar between said side platens in position to enter the welt crease at the end of said shoe.

40 19. A welt support unit comprising, a support adapted to be mounted in association with a shoe press, welt holding means on said support including a pair of platens each carrying a lower portion respectively adapted to enter respective portions of the welt crease around the sides and end of a shoe, the forward ends of said platens being overlapped and each having a laterally extending slot therethrough, and a post extending through said slots to connect said platens in pivotal and laterally slidable relation.

45 20. A welt support unit comprising a support adapted to be mounted on a shoe press, said support having a forwardly extending slotted tongue and laterally extending apertured wings, a front post extending through and downwardly from said slotted tongue, a plurality of platens shaped to extend around the forepart of a shoe in said press including side platens, side posts respectively connecting the rear portions of said side platens in supported relation with said apertured wings, at least one of said plurality of platens being mounted on said front post and having a pivotal connection with one of said side platens, said last named side platen overlapping the platen mounted on said front post, one of said overlapped platens having a laterally extending slot in its overlapped portion at said pivotal connection whereby it may be pivotally and bodily laterally moved, said plurality of platens carrying means at their lower portions for entering the welt crease around the forepart of said shoe to support the welt against pressure from below.

50 21. A welt support unit comprising a support adapted to be mounted in association with a shoe press, a plurality of rigid metal platens shaped to fit around the forepart of a shoe, means mounting said platens on said support for pivotal and lateral bodily movement with respect to each other, and a continuous rubber strip underlying said platens and adapted to enter the welt crease around the forepart of said shoe, said strip having its intermediate portion fixed to one of said platens adjacent the toe end thereof, and having its free ends respectively attached near the free ends of said platens by means of loose motion connections.

55 22. A welt support unit comprising a support adapted to be mounted in association with a shoe press, a plurality of rigid metal platens shaped to fit around the forepart of a shoe, means mounting said platens on said support for pivotal and lateral bodily movement with respect to each other, a continuous rubber strip underlying said platens and adapted to enter the welt crease around the forepart of said shoe, said strip having its intermediate portion fixed to one of said platens adjacent the toe end thereof, and having its free ends respectively attached near the free ends of said platens by means of loose motion connections, and springs normally urging the free ends of said strip rearwardly with respect to said platens.

60 23. A welt support unit comprising a pair of platens each carrying a lower portion respectively adapted to enter respective portions of the welt crease around the sides and end of a shoe, the forward ends of said platens being overlapped and each having a laterally extending slot therethrough, a post extending through said slots to connect said platens in pivotal and laterally slidable relation, a projecting ear pivotally mounted about a vertical axis on the forward portion of each of said platens, and an adjusting screw having right and left threaded sections respectively screwed in said pivotally mounted ears.

65 24. A welt support unit comprising a pair of platens adapted to enter the welt crease on opposite sides of a shoe, the forward ends of said platens being overlapped and each having a laterally extending slot therethrough, a post extending through said slots to connect said platens in pivotal and laterally slidable relation, and adjusting screw means pivotally connected with said platens to vary their laterally slidable re-

lation while permitting alteration of their pivotal relations.

25. A welt support unit, comprising a transverse bar, side platens fitted to enter the welt crease on opposite sides of a shoe each having an end pivotally mounted on said bar, at least one of said platens being also slidably along said bar for bodily movement toward and from the remaining side platen, and an end platen carried by said bar between said platens in position to enter the welt crease at the end of said shoe.

26. A welt support unit, comprising a transverse bar having a post extending upwardly therefrom, supporting means vertically slidably accommo-

dating said post, spaced side members fitted to enter the welt crease on opposite sides of a shoe each having its forward end attached to said bar, such attachment of at least one of said members being pivotal and laterally slidable with respect to said bar, said transverse bar having an end member spanning the space between the forward ends of said side members and fitted to enter the welt crease at the end of the shoe, additional posts respectively extending from said side members, and means vertically slidably supporting said additional posts.

JOHN F. SMITH.

WILLIAM C. CARD, JR.
